PRINTING BUSINESS MACHINE

John E. Ostline, Chicago, Ill., assignor to Automatic Electric Laboratories, Inc., Chicago, Ill., a corporation of Delaware

Original application April 13, 1942, Serial No. 438,760, now Patent No. 2,360,789, dated October 17, 1944. Divided and this application August 25, 1943, Serial No. 499,913

14 Claims. (Cl. 197—187)

The present invention relates to printing business machines and more particularly to such machines of the automatic printer or typewriter type. The present application is a division of my co-pending application Serial No. 438,760 filed April 13, 1942, now Patent No. 2,360,789, granted October 17, 1944.

It is the object of the present invention to provide in a printing business machine, including a movable support for a supply of paper stock, improved electromechanical paper testing mechanism for detecting the normal position of the supported supply of paper stock.

Another object of the invention is to provide in a printing business machine, including a support for a supply of paper stock, improved electromechanical paper mechanism for detecting the adequacy of the supported supply of paper stock.

A further object of the invention is to provide in a printing business machine, including a movable support for a supply of paper stock, improved electromechanical paper testing mechanism for detecting both the normal position of and the adequacy of the supported supply of paper stock.

Further features of the invention pertain to the particular arrangement of the mechanical elements of the different mechanisms incorporated in the machine, whereby the above-outlined and additional operating features are attained.

The invention both as to its organization and method of operating, together with further objects and advantages thereof, will best be understood by reference to the following specification taken in connection with the accompanying drawings, in which Figure 1 is a rear perspective view of a printing business machine constructed and arranged in accordance with the present invention; Fig. 2 is a plan view, partly broken away, of the rear portion of the machine shown in Fig. 1; Fig. 3 is a rear elevational view, partly broken away, of the machine; Fig. 4 is a side elevational view, partly broken away, of a paper supporting and guiding mechanism incorporated in the machine; Fig. 5 is a rear elevational view, partly broken away, of the mechanism shown in Fig. 4; Fig. 6 is a longitudinal sectional view, partly broken away, of the rear portion of the machine showing the assembly of the paper supporting and guiding mechanism and the paper cutting mechanism with reference to the platen and pressure rolls of the machine; Fig. 7 is a rear elevational view of paper position testing mechanism incorporated in the machine; and Fig. 8

is a side elevational view, partly broken away, of the mechanism shown in Fig. 7.

Referring now more particularly to Fig. 1 of the drawings there is illustrated a printing business machine 100 incorporating the features of the present invention. The illustrated embodiment of the machine 100 is in the form of an automatic printer or typewriter of the type known as the "Electromatic" typewriter having the general construction and arrangement shown in U. S. Patent No. 1,777,055, Russell G. Thompson, granted September 30, 1930.

The machine 100 comprises an upper main frame 101, a connected lower subframe 102 housing the power mechanism, a movable carriage 103 and a plurality of type levers 104. The power mechanism comprises the usual operating motor, power roll, clutch mechanism between the power roll and the type levers 104 and a plurality of operating keys. The subframe comprises casing structure 105 receiving the operating motor; while the main frame 101 supports a removable type hood 106 protecting the type levers 104. Also the main frame 101 carries a plurality of operating magnets adapted to control the associated operating keys and supports a removable magnet hood 107 protecting the operating magnets. The carriage 103 comprises the usual assembly including spaced-apart end walls 108 rotatably supporting a removable platen roll 109 provided with a resilient covering, formed of rubber or the like, and cooperating with type levers 104.

Further the machine 100 comprises paper supporting and guiding mechanism 110 and paper cutting mechanism 111, both carried by the carriage 103, and paper position testing mechanism 112 by the subframe 102.

Referring now more particularly to Figs. 1 to 3, inclusive, of the drawings, the carriage 103 is supported by the main frame 101 upon structure including the rear carriage rail 113 and comprises a marginal stop rack 114 extending between the end walls 108. The marginal stop rack carries two adjustable marginal stops 115 and 116, while the rear carriage rail 113 supports a fixture 117 upon which a tabulating lever 118 is pivotally mounted by a pin 119. The tabulating lever 118 carries an inturned projection 120 which cooperates with the lower ends of the two stops 115 and 116, whereby the marginal stops 115 and 116 are effective to establish the limit of travel of the carriage 103 in the two directions, the marginal stops 115 and 116 respectively comprising right-hand and left-hand marginal stops for

the carriage 103, as viewed from the front of the machine 100.

The tabulating lever 118 is mounted upon the pin 119 for both limited sliding movement transversely of the machine 100 in the direction of the rear carriage rail 113 and limited rocking movement toward and away from the rear carriage rail 113. As viewed in Fig. 2, the tabulating lever 118 is biased toward the left by a coil spring 121 extending between the fixture 117 and the tabulating lever 118, and also in a clockwise direction about the pin 119 by an arrangement comprising a rocking lever 122 pivotally mounted by a screw 123 upon the rear carriage rail 113. More particularly, the rocking lever 122 rests upon a plate 124 fixed to the top surface of the rear carriage rail 113 and comprises two arms 125 and 126. The lever 122 is biased in a counterclockwise direction about the screw 123, as viewed in Fig. 2, by an arrangement comprising a coil spring 127 surrounding the screw 123 and extending between the plate 124 and the arm 126; the arm 125 of the lever 122 being provided with an upstanding projection 128 engaging a leaf spring 129 secured to the adjacent end of the tabulating lever 118. At this point it is noted that the arm 126 of the lever 122 carries an upstanding dog 130 which cooperates with a part of the paper cutting mechanism 111, in a manner more fully explained in the above-mentioned pending application.

Also associated with the right-hand end of the tabulating lever 118 is a bell crank 131 pivotally supported upon the main frame 101 and biased away from the end of the tabulating lever 118 by a coil spring 132, the coil spring 132 extending between the bell crank 131 and the main frame 101. The bell crank 131 may be moved against the bias of the coil spring 132 toward the end of the tabulating lever 118, thereby to rock the tabulating lever 118 in the counterclockwise direction about the pin 119, as viewed in Fig. 2, under the control of a strap 133 secured thereto; the strap 133 being operated by the power roll of the machine 100 when the tabulating operating key is actuated by the associated operating magnet. Further the rear carriage rail 113 carries a latch 134 which is pivotally mounted upon a pin 135 and biased toward an abutment 136 formed on the left-hand end of the tabulating lever 118. Further it is noted that the left-hand end of the tabulating lever 118 carries an abutment 137 which also cooperates with the upstanding projection 128 provided on the arm 125 of the rocking lever 122.

Considering now the general operation of the machine 100, the carriage 103 normally occupies its right-hand marginal position, as viewed from the front, as determined by the position of the right-hand marginal stop 115 upon the associated marginal stop rack 114. As the operating magnets are selectively energized the corresponding operating keys are actuated, whereby the corresponding type levers 104 are selectively clutched to the power roll, assuming that the operating motor is running. As each type lever 104 is clutched to the power roll it is operated toward the platen roll 109 into striking engagement with the paper stock carried thereby in order to cause the associated type character to be printed thereon. The type lever is then automatically declutched from the power roll and is returned to its normal position; whereupon the carriage 103 is moved one space toward the left. When the return and line space operating magnet is

energized the associated operating key is actuated, whereby the carriage return and line space mechanism is first clutched to and then declutched from the power roll in order to cause the carriage 103 to be returned to its normal right-hand marginal position, as determined by the position of the right-hand marginal stop 115 upon the marginal stop rail 114, and to cause the platen roll 109 to be line spaced.

- 10 When the tabulating magnet is energized the associated tabulating operating key is actuated, whereby the tabulating mechanism is first clutched to and then declutched from the power roll, whereby the strap 133 is operated in order to cause the bell crank 131 to be pivoted against the bias of the coil spring 132 into engagement with the right-hand end of the tabulating lever 118. When the right-hand end of the tabulating lever 118 is thus depressed by the bell crank 131 the tabulating lever 118 is rocked in the counterclockwise direction about the pin 119, as viewed in Fig. 2, against the bias of the rocking lever 122. Also when the tabulating lever 118 is rocked in the counterclockwise direction about the pin 119 the latch 134 rides behind the abutment 136 provided on the left-hand end of the tabulating lever 118 in order to latch the tabulating lever 118 in the last-mentioned position and to release the carriage 103; whereby the carriage 103 is automatically moved toward the left, as viewed from the front of the machine 100. Also at this time the rocking lever 122 is rotated in the clockwise direction about the screw 123, as viewed in Fig. 2, against the bias of the coil spring 127 due to the action of the leaf spring 129 carried by the left-hand end of the tabulating lever 118 upon the upstanding projection 128 carried by the arm 125 of the rocking lever 122. When the rocking lever 122 is thus rotated in the clockwise direction the upstanding dog 130 carried by the arm 126 thereof is moved toward the platen roll 109 into cooperating relationship with respect to the paper cutting mechanism 111, in a manner more fully explained in the above-mentioned pending application.
- 15 When the carriage 103 is moved toward the left, as viewed from the front of the machine 100, to its left-hand marginal extremity, the left-hand marginal stop 116 carried by the marginal stop rack 114 engages the inturned projection 120 carried on the left-hand end of the tabulating lever 118; whereby the tabulating lever 118 is moved toward the right, as viewed in Fig. 2. When the tabulating lever 118 is moved toward the right, as viewed in Fig. 2, against the bias of the coil spring 121, the pin 119 permitting this movement of the tabulating lever 118 as previously noted, the latch 134 rides from behind the abutment 136 provided on the left-hand end of the tabulating lever 118. When the latch 134 rides from behind the abutment 136 provided on the left-hand end of the tabulating lever 118, thereby unlatching the same, the tabulating lever 118 is rotated in the clockwise direction about the pin 119, as viewed in Fig. 2, due to the bias exerted on the leaf spring 129 carried on the left-hand end thereof by the upstanding projection 128 carried on the arm 125 of the rocking lever 122. More particularly, the rocking lever 122 is rotated in the counterclockwise direction about the screw 123, as viewed in Fig. 2, by the coil spring 127; whereby the upstanding dog 130 carried by the arm 126 of the rocking lever 122 is moved out of cooperating engagement with respect to the paper cutting mechanism 111, for

a purpose more fully explained in the above-mentioned copending application. At this time the return and line space operating magnet may be again energized in order to effect the return of the carriage 103 to its normal right-hand marginal extremity, in the manner previously explained.

Referring now more particularly to Figs. 1, 4, 5, and 6 of the drawings, it is noted that the paper supporting and guiding mechanism 110 comprises a supporting bracket 150 having inturned ends 151 disposed between and removably secured to the end walls 108 of the carriage 103 by a plurality of screws 152. Also the mechanism 110 comprises an upstanding channel-shaped body 153, the upper end of which terminates in a substantially horizontal and inwardly disposed wall 154. Also the body 153 comprises side flanges 155, the lower ends of which terminate in outwardly and downwardly extending arms 156 arranged in substantially parallel spaced-apart relation. A shaft 157 extends through openings provided adjacent the outer ends of the arms 156 and is provided with removable knurled thumb nuts 158 threaded on the opposite ends thereof; the shaft 157 being adapted to support the spool 159 of a roll of ribbon-like paper stock 160. Also a substantially channel-shaped plate 161 is secured to the lower surface of the wall 154 by a number of rivets 162, the plate 161 having upstanding side flanges 163. The side flanges 163 of the plate 161 constitute a continuation of the side flanges 155 of the body 153, whereby a smooth guide channel is provided for the ribbon of paper stock from the roll 160.

Also the mechanism 110 comprises a substantially U-shaped supporting bracket 164 having upwardly and inwardly directed arms 165 arranged in parallel spaced-apart relation. The arms 165 constitute a support for the paper cutting mechanism 111 and carry two screws 166 by means of which the mechanism 111 is removably secured in place. More particularly, two aligned notches 167 are formed in the side flanges 155 of the body 153 and receive the center portion of the supporting bracket 150, while the center portion of the supporting bracket 164 engages the rear wall of the body 153; the body 153 and the brackets 150 and 164 being removably secured in assembled relation by two screws 168. More specifically, the two screws 168 extend through two spaced-apart holes provided in the supporting bracket 150 and are threaded into aligned tapped holes provided in the supporting bracket 164; whereby the body 153 is securely clamped between the brackets 150 and 164. Thus it will be understood that a narrow upwardly extending passage is formed between the bottom wall of the body 153 and the adjacent wall of the bracket 150 and between the side flanges 155 in order to receive and guide the ribbon of paper stock from the roll 160.

Further mechanism 110 comprises a paper tensioning element 169 including a base plate 170 and a substantially L-shaped inwardly disposed leaf spring member 171 secured together by a plurality of rivets or the like 172. The lower end of the base plate 170 is provided with an inwardly directed flange 173 which overhangs two aligned and spaced-apart pins 174 carried by the side flanges 155; thereby to provide a pivotal mounting for the lower end of the paper tensioning element 169. Also a rearwardly extending screw 175 is fixed to the bracket 150 and extends through an opening formed in the base

plate 170; the opening formed in the base plate 170 comprising an enlarged central hole 176 and a connecting restricted slot 177. Further the outer end of the screw 175 carries a thumb nut 178 which engages the base plate 170. This arrangement permits ready removal of the paper tensioning element 169 when the thumb nut 178 is sufficiently loosened due to the fact that the thumb nut 178 will pass through the hole 176 formed in the base plate 170 incident to lifting of the base plate 170. More specifically, when the thumb nut 178 is loosened the base plate 170 may be lifted and pulled rearwardly in order to cause the inwardly directed flange 173 to disengage the pins 174; whereby the thumb nut 178 may be passed through the hole 176 formed in the base plate 170, in an obvious manner.

Further it will be understood that the leaf spring member 171 engages the ribbon of paper stock adjacent the knee between the body 153 and the wall 154, thereby to tension the ribbon of paper stock; the amount of tensioning thereof depending upon the pressure exerted upon the paper tensioning element 169, which in turn may be oppositely determined by tightening and loosening the thumb nut 178 in an obvious manner.

Referring now more particularly to Figs. 1 and 6 of the drawings, it is noted that the paper cutting mechanism 111 comprises a substantially channel-shaped base 200 having downwardly turned side flanges 201 and an elongated rearwardly and downwardly extending paper chute 202 having upwardly turned side flanges 203; the base 200 and the paper chute 202 being suitably secured together by rivets or the like. The base 200 is secured to the two arms 165 of the supporting bracket 164 by means of the two screws 166 and two thumb nuts 204 threaded on the outer ends of the screws 166; the screws 166 passing through holes 205 provided in the base 200. Also a narrow elongated transverse slot is formed in the base 200 adjacent the front edge thereof. At this point it is noted that the front end of the paper chute 202 terminates adjacent the rear edge of the slot formed in the base 200 and that the paper guiding structure is secured to the base 200 adjacent the front edge of the slot formed therein by rivets or the like. More particularly, the paper guiding structure comprises a bottom wall having a downwardly and forwardly extending lip and a top plate 209 having downwardly turned side flanges 210. The paper guiding structure secured to the base 200 forwardly of the slot formed therein and the paper chute 202 secured to the base 200 rearwardly of the slot formed therein are arranged in alignment, whereby the ribbon of paper stock coming from the platen roll 109 of the machine 100 is fed through the paper guiding structure and across the slot formed in the base 200 and into the paper chute 202.

The paper cutting mechanism 111 is operated in a manner more fully explained in the above-mentioned copending application due to the co-operation between the downwardly extending lug 220 carried by the fixture 217 and the upwardly projecting dog 130 carried on the arm 126 of the rocking lever 122. More particularly, the dog 130 latches the lug 220 when the carriage 103 of the machine 100 occupies an operated position away from the left-hand marginal stop position thereof incident to the operation of the tabulating mechanism. When the tabulating mechanism is thus operated the dog 130 latches the lug 220, whereby the movable knife support 215 is

effectively locked to the frame 101 and the carriage 103 is returned to the left, as viewed from the front of the machine, to its left-hand marginal stop position. Accordingly the base 200 is moved from the right toward the left, as viewed from the front of the machine, while the movable knife support 215 is retained latched in a stationary position by the cooperation between the dog 130 and the lug 220. This movement of the base 200 toward the left effectively draws the knife blade 225 across the slot formed therein, whereby the ribbon of paper stock is severed in the manner explained above.

Referring now more particularly to Figs. 1, 7 and 8 of the drawings, it is noted that the paper position testing mechanism 112 comprises a base plate 250 which is removably secured to the sub-frame 102 of the machine 100 by means of a number of screws or the like rearwardly of the casing structure 105. Also the mechanism 112 comprises electromagnetic structure including a field element 251, a core 252, an armature 253 and a winding 254 carried by the core 252; the field element 251 being secured to the base plate 250 by two screws 255. The armature 253 is pivotally mounted upon a pivot pin 256 carried by a bracket 257 which is in turn secured to the field element 251 by a screw 258. Further the base plate 250 carries a plate 259 which is adapted to support a removable housing, not shown, for the mechanism 112. Further the armature 253 is provided with a rearwardly extending arm 260 which carries an insulator 261 on the outer end thereof; the insulator 261 cooperating with a suitable set of switch springs 262 carried by the field element 251.

Further a bar 263 is secured to the armature 253 by two screws 264 and is provided with an elongated slot 265 in the upper end thereof. The upper end of the bar 263 carries a paper roll contact rod 266 which extends through the slot 265 formed therein and is threaded into a tubular member 267. Also a lock nut 268 is threaded upon the rod 266. The arrangement above described permits ready adjustment of the rod 266 in the vertical direction toward and away from the end of the bar 263; also this arrangement permits ready adjustment of the end of the rod 266 toward and away from the bar 263. Accordingly the rod 266 may be readily adjusted toward and away from the axis of the shaft 157 supporting the roll of paper 160 in order to adjust the mechanism 112 to different sizes of cores of spools upon which the roll of paper 160 is wound. Also the rod 266 may be readily adjusted toward and away from the end of the paper roll 160 in accordance with the normal right-hand marginal stop position of the carriage 103 of the machine 100 as determined by the position of the right-hand marginal stop 116 carried by the marginal stop rack 114.

It will be understood that when the carriage 103 of the machine 100 occupies its normal right-hand marginal stop position, as viewed from the front of the machine 100, the roll of paper 160 carried by the paper supporting and guiding mechanism 110 engages the end of the rod 266, thereby to move the armature 253 of the paper position testing mechanism 112 toward the core 252. Further it will be understood that, when the winding 254 is energized, the armature 253 is attracted and moved toward the core 252. When the armature 253 is moved toward the core 252 the arm 260 carried thereby causes the insulator

261 to control the set of switch springs 262 for signaling purposes.

On the other hand, when the carriage 103 of the machine is moved away from its right-hand marginal stop position, as viewed from the front of the machine 100, the roll of paper 160 carried by the paper supporting and guiding mechanism 110 disengages the end of the rod 266, whereby the set of switch springs 262 tends to move the armature 253 away from the core 252 due to its resiliency. Similarly, when the winding 254 is de-energized the set of switch springs 262 tends to move the armature 253 away from the core 252. When the armature 253 is moved away from the core 252 the set of switch springs 262 is controlled in the opposite sense for signaling purposes. Thus it will be understood that, when the winding 254 is energized or the roll of paper 160 engages the rod 266, the armature 253 is moved toward the core 252; and that, when the winding 254 is de-energized and the roll of paper 160 disengages the rod 266, the armature 253 is moved away from the core 252; whereby the set of switch springs 262 is selectively controlled.

During the operation of the machine 100, when the carriage 103 thereof occupies its normal right-hand marginal stop position, as viewed from the front of the machine 100, and there is ample paper stock upon the paper roll 160, the rod 266 is engaged, thereby to move the armature 253 toward the core 252. When the machine 100 is seized for use the winding 254 is energized, thereby to retain the armature 253 attracted toward the core 252. Subsequently, after the complete operation of the machine 100, the carriage 103 thereof is operated toward its right-hand marginal stop position and the winding 254 is de-energized. At this time the armature 253 remains in its position adjacent the core 252 only in the event that the carriage 103 of the machine 100 is moved fully to its right-hand marginal stop position and in the additional event that there is adequate paper stock upon the roll 160 in order to engage the rod 266. Hence it will be understood that, at the conclusion of the operation of the machine 100, in the event the carriage 103 thereof is not returned completely to its right-hand marginal stop position or there is inadequate paper stock upon the roll 160, the rod 266 is not engaged and the armature 253 is moved away from the core 252; whereby a suitable signal is controlled in order to indicate that one of the conditions mentioned above exists and that the machine 100 is accordingly not in readiness for subsequent reoperation.

Again considering Figs. 1 and 6 of the drawings, it is pointed out that, in the machine 100, the ribbon of paper stock extends from the roll 160 rotatably supported by the shaft 157, forming a part of the paper supporting and guiding mechanism 110, up through the guide channel formed between the supporting bracket 150 and the upstanding channel-shaped body 153 and then in a substantially horizontal direction across the horizontal wall 154 to a horizontal transversely extending paper guide 300 incorporated in the structure of the carriage 103. The ribbon of paper stock continues from the paper guide 300 between the platen roll 109 and a horizontal transversely extending pressure roll 301, incorporated in the structure of the carriage 103, and thence around the platen roll 109 and between the platen roll 109 and a horizontal transversely extending paper shield 302. The paper shield 302 is suitably secured by a series

of rivets 303 to a paper guide 304 incorporated in the structure of the carriage 103. Also it is noted that the paper shield 302 has an elongated slot 305 formed therein, whereby the surface of the paper disposed below the slot 305 is adapted to be contacted by the type levers 104. The tension exerted upon the ribbon of paper stock feeding from the roll 160 and between the platen roll 109 and the pressure roll 301 may be adjusted by tightening or loosening the thumb screw 178 in order to cause the leaf spring member 171 to exert more or less pressure upon the ribbon of paper stock as it passes over the knee disposed between the upstanding channel-shaped body 153 and the horizontal wall 154, in the manner previously explained. After the ribbon of paper stock passes between the paper shield 302 and the plate roll 109 it extends into the paper guiding structure, forming a part of the paper cutting mechanism 111 and including the bottom wall 207 and the top wall 209, and over the slot 206 formed in the base 200 into the paper chute 202. The strip of the ribbon of paper stock extending beyond the slot 206, formed in the base 200, and into the paper chute 202 may be readily severed by operating the paper cutting mechanism 111, in the manner previously explained, whereby the severed strip of the ribbon of paper stock may slide down the downwardly and rearwardly inclined paper chute 202 into a suitable receptacle. At this point it is noted that the guiding surfaces of the paper supporting and guiding mechanism 110, as well as the guiding surfaces of the paper cutting mechanism 111, are highly polished in order to minimize the frictional drag exerted upon the ribbon of paper stock passing therover. Also the interior surface of the paper chute 202, forming a part of the paper cutting mechanism 111 is highly polished, whereby the strip of severed paper stock may slide down the inclined paper chute 202 due to the action of gravity and be received by a suitable receptacle.

At this point it is noted that both the shaft 157, forming a part of the paper supporting and guiding mechanism 110, and the paper chute 202, forming a part of the paper cutting mechanism 111, are disposed rearwardly of the rear wall of the subframe 102. More particularly, the arms 156 of the paper supporting and guiding mechanism 110, which support the shaft 157, extend through a rectangular opening 306 formed in the rear wall of the subframe 102; the opening 306 formed in the rear wall of the subframe 102 extending transversely thereacross a distance sufficient to accommodate the normal travel of the carriage 103 of the machine 100. The paper chute 202 of the paper cutting mechanism 111 extends over the rear marginal edge of the main frame 101; whereby the receptacle which is adapted to receive the severed strips of the ribbon of paper stock may be disposed rearwardly and clear of the machine 100.

Considering now the operation of the tabulating mechanism incorporated in the machine 100 in conjunction with the operation of the paper cutting mechanism 111, reference is again had to Figs. 1 to 3, inclusive, of the drawings. At the conclusion of a complete printing operation of the machine 100 the carriage 103 occupies a position displaced from the right-hand marginal stop position thereof, as viewed from the front of the machine 100, corresponding to one space beyond the last character printed upon the last line of the section of paper stock appearing in the slot 305 formed in the paper shield 302, as will be

readily understood. At this time the "return" and "line space" operating magnet is energized a plurality of times, whereby the carriage 103 is returned to its normal right-hand stop position and the platen roll 109 is spaced a corresponding plurality of times; whereby the section of paper stock upon which the printing matter appears is fed from between the paper shield 302 and the platen roll 109 through the paper guiding structure, forming a part of the paper cutting mechanism 111, and beyond the slot formed in the base 200 and into the paper chute 202. At this time the carriage 103 of the machine 100 occupies its normal right-hand marginal stop position and the tabulating operating magnet is energized; whereupon the carriage 103 is automatically moved from its right-hand marginal stop position to its left-hand marginal stop position. More particularly, when the tabulating mechanism incorporated in the machine 100 is thus operated, the rocking lever 122 is rotated in the clockwise direction about the screw 123, as viewed in Fig. 2, by the operation of the tabulating lever 118, and the tabulating lever 118 is restrained in its operated position by the latch 134, in the manner previously explained. When the rocking lever 122 is rotated in the clockwise direction about the screw 123, as viewed in Fig. 2, the dog 130 carried by the arm 126 thereon is moved forwardly toward the platen roll 109 and into such a position that it is disposed in the path of movement of the downwardly projecting lug 220 formed on the fixture 217 carried on the left end of the movable knife support 215, as shown in Fig. 6. As the carriage 103 moves toward the left, the lug 220 hangs upon the dog 130, whereby further movement of the knife support 215 is arrested. However, the carriage 103 continues to move toward the left, whereby the remainder of the cutting mechanism 111, including the base 200, is moved therewith. When the base 200 is thus moved toward the left, while the knife support 215 is held in a stationary position, the knife blade 225 is effectively drawn through the slot formed in the base 200, whereby the section of the ribbon of paper stock disposed beyond the slot and in the paper chute 202 is severed. The last-mentioned section of the ribbon of paper stock includes the matter printed thereupon due to the last operation of the machine 100. Accordingly, the severed strip of the ribbon of paper stock including the printed matter, due to the last operation of the machine 100, comprises a ticket which slides down the paper chute 202 into a suitable receptacle.

Subsequently, when the carriage 103 is completely returned to its left-hand marginal stop position the tabulating lever 118 is released due to its movement with respect to the pin 119; whereupon the latch 134 rides from behind the abutment 136 provided on the left-hand end of the tabulating lever 118, in the manner previously explained. At this time, when the tabulating lever 118 is released, the rocking lever 122 is rotated in the counterclockwise direction about the screw 123, as viewed in Fig. 2, by the coil spring 127, whereby the upstanding dog 130 provided on the arm 126 disengages the downwardly extending lug 220 carried by the fixture 217, forming a part of the movable knife support 215. When the dog 130 disengages the lug 220 the knife support 215 is released and is returned toward the left to its normal position. At this time, the paper cutting mechanism 111 has completed its operation and occupies its normal

position. The return and line space operating magnet is then energized in order to cause the carriage 103 to be returned to its normal right-hand marginal stop position. At this time the machine 100 is completely released and is available for further use for the next printing operation.

The operation of the paper position testing mechanism 112 incident to the operation of the machine 100 is fully described above, and in the interest of brevity is not again repeated.

While one embodiment of the invention has been disclosed, it will be understood that various modifications may be made therein which are within the true spirit and scope of the invention.

What is claimed is:

1. A business machine comprising printing mechanism, a movable member having a normal position and adapted to support a supply of paper stock, means for feeding said paper stock from said member into printing relation to said printing mechanism, an electromagnet including field structure provided with a winding and a movable armature, said armature being biased to a first position and operative to a second position, the operation of said armature to its second position being controlled in accordance with the energization of said winding only when said machine is being operated, means including a paper testing element adapted to cooperate with said supply of paper stock for operating said armature to its second position only when said member occupies its normal position and said electromagnet winding is deenergized, and contacts controlled for signal purposes in response to the movement of said armature to its first position.

2. A business machine comprising printing mechanism, a member adapted to support a supply of paper stock, means for feeding said paper stock from said member into printing relation to said printing mechanism, an electromagnet including field structure provided with a winding and a movable armature, said armature being biased to a first position and operative to a second position, the operation of said armature to its second position being controlled in accordance with the energization of said winding only when said machine is being operated, means including a paper testing element adapted to cooperate with said supply of paper stock for moving said armature to its second position only when said member supports an adequate supply of said paper stock and said winding is deenergized, and contacts controlled for signal purposes in response to the movement of said armature to its first position.

3. A business machine comprising printing mechanism, a movable member having a normal position and adapted to support a supply of paper stock, means for feeding said paper stock from said member in printing relation to said printing mechanism, an electromagnet including field structure provided with a winding and a movable armature, said armature being biased to a first position and operative to a second position, the operation of said armature to its second position being controlled in accordance with the energization of said winding responsive to said machine being taken for use, means including a paper testing element adapted to cooperate with said supply of paper stock for moving said armature to its second position only both when said member occupies its normal position and supports an adequate supply of said paper stock, and contacts controlled for signal purposes in

response to the movement of said armature to its first position in the event that said winding is deenergized and said armature is not maintained in its second position by said last mentioned means.

4. A business machine comprising printing mechanism, a movable shaft having a normal position and adapted to support a hollow roll of paper stock, means for feeding said paper stock from said roll into printing relation to said printing mechanism, an electromagnet including field structure provided with a winding and a movable armature, said armature being biased to a first position and operative to a second position, the operation of said armature to its second position being controlled in accordance with the energization of said winding during operation of said machine, means including a testing element adapted to cooperate with the edges of the paper stock forming the side of said roll for moving said armature to its second position only both when said shaft occupies its normal position and said roll contains an adequate supply of paper stock, and contacts controlled for signal purposes in response to the movement of said armature to its first position in the event said last mentioned means has failed to maintain said armature in its second position after said winding is deenergized.

5. A business machine comprising printing mechanism, a movable shaft having a normal position and adapted to support a hollow roll of paper stock, means for feeding said paper stock from said roll into printing relation to said printing mechanism, an electromagnet including field structure provided with a winding and a movable armature, said armature being biased to a first position and operative to a second position, the operation of said armature to its second position being controlled in accordance with the energization of said winding during the period of time said machine is being operated, means including a testing element carried by said armature and adapted to cooperate with the edges of the paper stock forming said roll for maintaining said armature in its second position only both when said shaft occupies its normal position and said roll contains an adequate supply of paper stock, means for adjusting said testing element toward and away from the edge of said roll, thereby to accommodate different normal positions of said shaft and corresponding different widths of said roll, means for adjusting said testing element toward and away from the axis of said shaft, thereby to accommodate different size hollow rolls of paper stock corresponding to different core diameters of said roll, and contacts controlled for signal purposes in response to the movement of said armature to its first position in the event said testing means has failed to maintain said armature in its second position after said winding is deenergized.

6. A business machine comprising a printing mechanism, a movable carriage having a normal position, a relay supported by said machine, a testing device having a first position and a second position, said relay being energized during the period of time said machine is being operated for maintaining said testing device in said first position, said carriage after said relay has been deenergized adapted to maintain said testing device in said first position in the event said carriage has restored to its normal position, and contacts controlled by said testing device when moved to said second position for indicating

that said carriage has failed to restore to normal.

7. In a printing machine, a movable carriage having a normal position, a testing device having a first position and normally biased to a second position, said carriage in its normal position adapted to maintain said device in said first position, means for maintaining said device in said first position while said carriage is in an off-normal position during the period of time said machine is being operated, and means controlled by said testing device in its second position for indicating that said carriage is in an off-normal position.

8. In a printing machine, a movable carriage having a normal position, a testing device having a first position and normally biased to a second position, said carriage in its normal position maintaining said device in said first position, means for maintaining said device in said first position while said carriage is in an off-normal position during the period of time said machine is being operated, and means controlled by said testing device responsive to the failure of said carriage to occupy its normal position at the conclusion of the operation of the machine for indicating that said carriage is in an off-normal position.

9. In a typewriter, a movable carriage having a normal position, a testing device having a first position and a second position, an electromagnet energized only during the typing operation of said machine to maintain said testing device in said first position, means supported by said carriage to maintain said testing device in said first position during the period of time said machine remains unoperated, and means controlled by said testing device when moved to said second position for indicating that said carriage has failed to return to its normal position after the typing operation has been terminated.

10. In an electric typewriter, a movable carriage having a normal position, a support for a supply of paper stock carried by said carriage, a testing device having a first position and a second position, an electromagnet normally energized during the typing operation of said machine and deenergized at the conclusion of the typing operation, said electromagnet in its energized position maintaining said device in said first position, said testing device being maintained in said first position by cooperation with the edges of the paper supply when said carriage is in its normal position, and means effective responsive to the deenergization of said electromagnet for moving said testing means to said second position for signaling purposes in the event either said carriage fails to occupy its normal position at the conclusion of the typ-

ing operation or said supply of paper stock is inadequate for further typing operation of said machine.

11. In an electric typewriter, a movable carriage having a normal position, a paper roll carried by said carriage, a testing element adapted to cooperate with the edges of the paper constituting said paper roll, said testing element having a first and a second position, an electromagnet adapted to maintain said testing element in said first position during the period of time said machine is being operated, said paper roll adapted to maintain said element in its first position during the period of time said machine remains unoperated with said carriage in its normal position, and means controlled in the event the supply of paper on said paper roll becomes inadequate for moving said element to said second position to give an indication thereof.

12. In a typewriter, a movable carriage having a normal position, a supply of paper stock carried by said carriage, a tester for determining the adequacy of the supply of paper stock when said carriage is in said normal position, a magnet for maintaining said tester in a first position only during the time said machine is performing a typing operation, means for restoring said carriage to its normal position after said typing operation has been completed, and contacts controlled by said tester when said carriage is in its normal position in the event said supply of paper stock is inadequate for another typing operation for completing a signal indicative of the inadequacy of said paper supply.

13. In a business machine comprising a roll of paper and a movable carriage causing relative movement between an operating mechanism and the paper, a testing device, a magnet, means for operating said magnet during operation of the machine to prevent the functioning of said device, said device rendered effective upon cessation of operation of the machine to operate a signal in the event the paper supply is low or the machine has failed to return to normal position.

14. In a business machine comprising a roll of paper and a movable carriage causing relative movement between an operating mechanism and the paper, a testing device for determining that the carriage is in normal position and that there is an adequate supply of paper on the roll, and means for rendering said testing device ineffective during operation of the machine and for rendering said device effective upon cessation of operation of the machine to operate a signal in the event the supply of paper is inadequate or the carriage has failed to return to normal position.

JOHN E. OSTLINE.
